METER READING APPARATUS

Paul Yates, Pittsburgh, Pa.

Application April 30, 1931, Serial No. 533,988

1 Claim. (Cl. 177—351)

This invention relates to the reading of meters, and consists in means which permit a dial, or a plurality of dials, to be read at a point remote from its location. In my application for Letters 5 Patent Serial No. 416,373, filed Dec. 26, 1929, now Patent 1,897,657 issued February 14, 1933, I have described how the reading of a gas meter, a water meter, an electrical meter or the like, may be made over an electrical communication 10 system, such, for example, as the Bell Telephone System. The objects of the present invention are in general the same as those stated in the above noted application. A further object, is, however, in mind; it is to provide means for 15 controlling at the central reading station the operation of the remotely situated meter-reading instrumentalities. These and other objects will be amplified and more fully explained in the following specification.

20 In the accompanying drawing there is shown a diagram, and in such diagram there are indicated a numbered dial and its pointer or hand, a telephone system, and means associated with the telephone system and the dial for indicating, at a 25 distance from the dial, the position of the pointer. In my co-pending application I have taught that the reading of a meter may be effected through the function of an electrical, sound-producing mechanism. The sounds which signify 30 the reading of the meter or dial may be audible words or merely sound signals. These meter-reading sounds are generated or reproduced at the receiving or reading station by the reaction of electrical impulses upon a diaphragm. Electrical 35 impulses are also necessary to effect the reading of a dial in accordance with the present invention, but it is the magnitude or character of the impulses themselves upon a recording device or a visual indicator, which affords significance. In 40 other words, I combine with a meter dial, means for creating electrical impulses upon a communication circuit. The electrical impulses which are so created are of a regulated character, and may with a suitable instrument be distinguished one 45 from the other. With each position which the dial pointer may take, impulse-creating means are coordinated, and such impulse-creating means are adapted to effect the creation of a distinctive electrical impulse (or impulses) in accordance 50 with the position of the dial pointer.

55 Referring to the drawing an embodiment of the invention will be described. The dial 1 has ten contact pieces 2, there being one contact piece for each of the ten positions which the pointer 3 may take. The contact pieces are electrically insulated one from the other, and are each connected in numerical sequence to a contact 4 of the series of aligned contacts which are secured to a support 5 of insulating material. Upon a threaded shaft 6 is a carriage 7; a motor 8 is 55 geared to effect the rotation of the shaft 6, and according as the shaft rotates, the carriage 7 travels thereon. A brush 9 is borne by the carriage 7, and, as the carriage travels, the brush 9 progressively makes and breaks contact with the several contacts 4. The pointer 3 is electrically connected by a wire 10 to the one wire (11) of the subscriber's telephone line, and, as will presently be described, during operation of the meter-reading device the brush 9 is connected by 15 a wire 12 to the other wire (13) of the telephone line.

To the end that the apparatus may be clearly understood, the process of reading the meter dial 1 in the remotely located power company's office A 20 will be outlined. The attendant, either by mechanical or manual switching in the telephone exchange, obtains telephone connection with the subscriber's telephone, the particular dial that the attendant wishes to read being connected to the 25 lines of such subscriber's telephone. Such connection being made, it is then necessary to energize the motor 8, and to move the brush 9 over the series of contacts 4. Advantageously, means are provided to disconnect the subscriber's telephone while the reading is going on, and, obviously, it is of advantage to effect such control in the power company's office A. To this end the 30 wires 13, 13', 13'' of the telephone company's line are interconnected, as indicated at 14. (Such 35 interconnecting of telephone wires is common practice where a telegraph system is operated over telephone lines, and it is expedient only when the telephone system is inductively coupled through the telephone exchange.) To these directly interconnected lines 13, 13', 13'' one terminal of a high frequency alternator 15 is connected, the frequency and general characteristics of the alternator being such that no "cross-talking" or 40 any other objectionable effect is produced to interfere with the normal operation of the telephone system. The other terminal of the alternator is connected to a grounded switch 16. At the subscriber's end of the telephone line two 45 relays 17 and 18 each have one terminal connected by a wire 20 to the line 13', 13'', and the other terminal leading to the ground. These relays are such in structure as to be sensitive to the effect of the current of the alternator, normal operating 50 currents and electrical impulses of the tele-

phone circuit do not disturb the relays from their normal, illustrated position, that is, the position which renders the meter-reading instrumentalities inactive, and maintains the telephone circuit in condition for normal operation. To obtain a reading the attendant closes the switch 16. The closing of switch 16 causes the relay 17 to function and to open the line 13, and to complete connections between the wire 13' and the wire 12. Simultaneously, relay 18 functions to close connections from a suitable source (19) of energy to the motor 8. The source 19 of energy is represented in the drawing as a battery, but of course suitable connections may be made to an electric power line instead of a battery for the energization of the motor. The position of rest of the carriage 7, that is, the location of the carriage before the start of a reading, is at the left-hand end of the shaft 6, where the brush 9 is in engagement with the contact 100, which contact will be later described. So, when the switch 16 is closed the motor 8 is caused to revolve, moving the carriage in a left-to-right direction and causing the brush 9 to contact successively each member 4. Until the brush 9 engages that particular member 4 which is connected by its associated wire 21 to that contact piece 2 with which the pointer 3 is in engagement, the telephone circuit will remain incomplete and no effect will be had. When, however, the brush 9 strikes the contact 4 which is coordinated with the position of the dial pointer, a circuit is closed across the subscriber's telephone lines. That is to say, when the brush 9 strikes the contact 4 which it is shown to be contacting in the drawing, a circuit is established through its associated wire 21, contact 2, and pointer 3, whence through the conductor 10 to the one telephone line 11; and the circuit is completed by means of the wire 12 interconnecting the brush 9 and the other telephone line 13', this being done, of course, through the relay 17. The closing of a circuit, such as a telephone circuit, causes an electric impulse to travel over the telephone wires. The character of the impulse, which the closing of a circuit through one pointer position creates, may be and is distinct from the impulse created by the closing of the telephone circuit through any other pointer position. Conveniently, a resistance ($R_0, R_1, R_2 \dots$) is included in each line 21, the electrical value of the resistances in the lines being graduated in correspondence to the position of their associated dial contacts 2, as shown in the drawing. Hence, the closing of the circuit through the pointer 3, when it reads zero, will create a minimum impulse in the circuit. This is so because R_0 is of greatest resistance relative to the other resistances ($R_1, R_2 \dots$). The impulse created by closing the circuit when the dial reads "1" is greater than the "zero" impulse; the impulse of dial reading "2" is greater than that of dial reading "1", etc. In the reading room of the power company, light signals, relays, photo-electric cells, recording devices, galvanometers, or other of such well known devices may be hooked-up with the telephone lines according to engineering practice, and caused to operate in correspondence with the magnitude of an electric impulse. So, the reading of the meter dial may be signified. I have shown diagrammatically a galvanometer B as the signaling device. The switch b, manifestly, is swung from its horizontal position to a vertical position to bring the galvanometer into proper electrical relation. The impulse created by the brush engaging the contact 4, which is associated with

the dial numeral "2", is effective to move the galvanometer pointer to the numeral "2" on its scale, thus signifying the reading of the meter dial 1. In like manner the closing of a circuit through any of the possible positions of pointer 3 is effective to create an electrical impulse which will deflect the galvanometer B in accordance with the reading of the dial. The galvanometer indicating hand may include a mirror, and a beam of light may be deflected by the mirror to magnify the effective movement of the galvanometer's indicator. Such an adaptation of a mirror has been practiced for years and no illustration is deemed necessary.

If the meter has a plurality of dials, manifestly, a sufficient number of contact pieces 4 may be organized on a support 5 and so connected to the several dials consecutively that each position of each dial pointer can be ascertained over a telephone system (see application Serial No. 581,134, filed December 15, 1931), now Patent 1,955,043 issued April 17, 1934. To compensate for the resistances and impedances, etc. of the telephone system, each meter reading device is when installed balanced with the galvanometer by means of an adjustable resistance RR.

When the carriage 7 has continued in its left-to-right direction until the brush 9 has contacted all the pieces 4, a reversing switch 50 is operated to effect the reverse rotation of the motor and the return of the carriage to starting position at the left-hand end of the shaft 6. The reversing switch may be in structure a well-known "star" switch. Conveniently a lever 51 is pivotally secured at 52 to a fixed support (not shown), and the lower end of this lever is pivotally secured in an obvious manner to the throwing arm of the reversing switch. The upper end of the lever 51 is pivotally connected at 53 to a trip-rod 54, and when the carriage contacts the last of the contact pieces 4, it strikes the protuberance 55 on the trip-rod, rotates the lever 51 clockwise, and springs the switch 50 to its alternate position. Then, the motor is reversed and the carriage returns to starting position.

Means are provided to notify the meter reader in office A when the carriage has reached starting position. Such means include a buzzer or automatic make-and-break device 60 which is connected in an electrical sense to the wire 10 and the contact 100. When the carriage approaches its starting position, the brush 9 makes contact with the contact piece 100, and completes a circuit through the buzzer 60 to the telephone lines 11 and 13'. In the office A there is a loud speaker S, and the operation of the buzzer causes the indicator S to sound out the fact that the carriage has reached, or practically has reached its starting position. The meter reader then opens switch 16 which causes the relays 17 and 18 to return to their illustrated position, leaving the telephone circuit in normal condition. A transmitter 120 may be included in the line 12 to enhance the desired transmission of electrical impulses.

There is a protuberance 56 on the left-hand end of the trip-rod 54, and if the key 16 is opened before the carriage 7 has during its return movement struck the protuberance 56, the carriage will continue its right-to-left (return) movement when the key 16 is depressed for another reading. That is to say, the carriage will continue its return motion until the projection 56 is struck and the trip-rod is shifted to throw the lever 51 and the reversing switch to such position that

the motor 8 is caused to effect the movement of the carriage in a left-to-right direction on the shaft 6, as first explained. Thus it will be seen that one person can obtain and control the reading of meter dials at a station far remote from the meters.

I claim as my invention:

In a telephone system including a telephone at a meter-reading station, a remotely-located subscriber's telephone, and a telephone-switching exchange connected by telephone lines to each of said telephones, said telephone exchange including means for coupling said telephone lines, the combination of a meter including a metering instrumentality movable progressively from one metering position to another, a series of incomplete circuits having terminal contacts correlated with the metering positions of said instrumentality, means for establishing electrical communication between said incomplete circuits and the subscriber's telephone line, means for closing said

incomplete circuits, which means include an electrical brush, brush-moving mechanism for sweeping said brush with automatically-progressive movement over said contacts and restoring it to its initial position, thereby creating at least one signalling impulse in said telephone system, a receiver responsive to electric impulses, means for electrically coupling said receiver to the telephone line of said meter-reading station, control means electrically coupled to the telephone line of said meter-reading station, said control means including an electric instrumentality for producing electric oscillations in said telephone system without the normal operating frequencies of the system and distinct from the impulses in response to which said receiver operates, and means organized with said subscriber's telephone line and responsive to said electric oscillations for effecting the energizing of said circuit-closing means for the series of incomplete circuits.
